COIN CONTROLLED TOY BANK

Harlow B. Grow, Linden, Mo.

Application October 16, 1947, Serial No. 780,209

6 Claims. (Cl. 46—4)

1

This invention relates generally to a coin controlled mechanism, applicable to coin receptacles of any kind, and capable of employment in connection with toy banks.

One of the objects of the present invention is to provide a simple, effective and especially inexpensive type of a coin controlled mechanism adapted to visually or otherwise indicate or determine the denomination of a coin placed therein by its thickness, and whereby such coin, irrespective of its thickness, is adapted to actuate the mechanism to perform certain functions.

A more specific object of this invention is to provide such coin controlled mechanism in combination with other devices, such as a toy bank, for not only indicating the denomination of a coin inserted therein, but for performing other desired functions.

A further, more specific object of this invention is to provide a toy bank equipped with a coin controlled mechanism composed of two co-acting elements, and wherein parts of the mechanism are adapted to normally interlock with one another, and are further adapted to become released by the insertion of a coin.

The foregoing and still other objects and advantages of the present invention will become more readily apparent from the ensuing description, in conjunction with the accompanying drawings, wherein:

Fig. 1 represents a perspective view of a presently preferred form of a toy bank in the form of a toy house;

Fig. 2 is a section taken on a vertical plane indicated by line 2—2 in Fig. 1;

Fig. 3 is a section taken on a vertical plane indicated by line 3—3 in Fig. 2 with a portion of the coin chute, representing the chimney, broken off;

Fig. 4 is a fragmental sectional detail plan view of the coin controlled mechanism employed in the toy bank, taken on line 4—4 of Fig. 2 and showing the mechanism in one position;

Fig. 5 is a partial vertical cross sectional detail view, taken approximately on line 5—5 of Fig. 3;

Fig. 6 is a plan view, partly in cross section similar to that shown in Fig. 4, with the mechanism in another position; and

Fig. 7 is a diagrammatical detail view of a portion of the coin controlled mechanism adapted for determining the denomination of coins inserted into the mechanism by the thickness of the coins.

Referring now more specifically to the figures, numeral 10 designates a coin receptacle, shown in

2

the present illustrations in the form of a toy house, which constitutes a substantially fully closed coin receiving chamber, provided with a coin removal opening 11, which is normally rendered inaccessible by a closure 12 controlled by a lock arrangement 13, as shown at the bottom of Fig. 3. The coin bank may be constructed of either translucent or opaque material, or both, and, when made from opaque material, there may be provided windows at one or more walls of the structure, such as indicated in wall 14 at 15 of Fig. 3. Opposite window 15 there is preferably arranged a door opening 16 permanently and completely covered from the inside by a transparent member 17. Operative in opening 16 is a closure or door 18 which is normally held in closed position by a spring hinge 19. A suitable handle 20 facilitates manual opening of the door when the latter is released for such operation, as will be presently explained.

Secured to the upper edge of door 18 is an arcuate detent element 21 composed of a larger arcuate portion or quarter segment 22 and a similar smaller portion or quarter segment 23, which latter is operative in a slot 24 cut out from transparent covering 17.

The difference in radii between the larger and smaller segments 22 and 23 of the detent provides in that structure a step formation constituting an abutment 25 which is intended to serve two distinct purposes, as will become presently evident. Arranged on the top surface and the end remote from abutment 25 of larger portion or segment 22 of the detent element is a wedge-shaped member 26.

Extending from and above the roof of the toy bank is a substantially tubular coin chute 27 in the form of a chimney in which are provided two vertical slots, disposed at right angles to one another. One, the longer slot 28, is the coin receiving slot, whereas the shorter slot 29 serves for accommodating a curved lever 30 adapted to be operated by coins inserted into slot 28. Lever 30 constitutes the inner arm of a bell crank structure 31, pivoted at 32, the other or outer arm of the bell crank being indicated at 33. This outer arm terminates in a hook 34 adapted to cooperate with abutment 25 and wedge member 26 of detent 21. A spring element 35 secured between outer arm 33 and chimney extension 36 normally urges bell crank structure 31 in one, that is, in clockwise direction when observed from the side seen in Fig. 2. Due to the tension of the spring inner arm 30 is urged towards end wall 37 of chimney 27, whereas hook 34 is kept in engage-

ment with abutment 25 of detent element 21. As stated, abutment 25 of the detent serves two purposes. One purpose of the abutment is to retain detent element 21 in one of its end positions at which door 18 is closed, whereby the latter is prevented from being manually opened, see Fig. 4. The other purpose of abutment 25 is to hold detent 21 in its other end position at which it serves as end stop for the manually opened door in the manner indicated in Fig. 6. In the first end position abutment 25 becomes engaged by hook 34, whereas in the other end position abutment 25 engages tapered surface portion 38 provided at the upper center of transparent cover 17.

As seen from Figs. 2, 3 and 5, the upper surface of chimney 27 is preferably equipped with a cover 39 which extends over and obscures transverse slot 29, while leaving accessible longitudinal slot 28 for the insertion of coins.

Operation of the toy bank

Prior to the insertion of a coin into the toy bank the different operating parts of the device are held in their initial position shown in Figs. 2, 3, 4 and in Fig. 5 in full lines. Thus door 18, normally closed by spring hinge 19, is additionally held in that closed position by the engagement of hook 34 with abutment 25 of detent 21. Hook 34 of lever arm 33 is kept in engagement with abutment 25 by the tension of spring 35. At the same time coin operated lever arm 30 is urged towards end wall 37.

When now a coin is inserted through slot 28 lever arm 30 is moved in a direction opposite to that induced by the spring, that is to the left, as indicated in full lines in Fig. 5. (Compare the two positions of bell crank lever arms 30 and 33 in Figs. 2 and 5.) While arm 30 is forced to the left, hook 34 disengages abutment 25, thus releasing detent 21. Due to this release of the detent door 18 may be now manually opened to the position indicated in broken lines in Fig. 5 and in full lines in Fig. 6. During the manual opening of the door, detent 21 swings about its fulcrum, which is spring hinge 19, through an arc of, say, 75 degrees, and during this outwardly swinging motion the coin, indicated in full lines at "C" in Fig. 5, is temporarily held in slot 28 by inner lever arm 30 due to the tension exerted by spring 35. As door 18 nears its fully open position, shown in Fig. 6, wedge-shaped element 26 is brought beneath hook 34 of lever arm 33 and raises that hook and the arm to the position indicated in broken lines in Fig. 5. The upward movement of lever 33 also causes inner lever arm 30 to move from its full-line position to the left and to assume the position indicated in broken lines. At that position of lever 30 coin "C" is released and is permitted to drop in the direction of the arrow into the interior of the toy bank. During the period the coin is released, door 18 is kept open to its extreme position, its opening movement being limited by the engagement of abutment 25 with tapered surface 38 of transparent cover 17. Thus the coin dropping into the bank may be readily observed through that transparent member.

Referring now to Fig. 1, there will be seen arranged at the side of chimney 27 an indicator and a scale denoted at 40. In Fig. 7 a diagram illustrates the bell crank arrangement 31. The end of lever arm 30 of the bell crank is engaged by one end of a reciprocatingly mounted rod 41 operating in a guide 42. The opposite end of rod 41

engages the upper end of indicator 43 hinged at 44 and urged towards lever arm 30 by spring 45. The lower end of indicator 43 is movable over a scale 46 on which are provided letters designating the different thicknesses of a dime, a penny, a nickel and a quarter. Thus when a coin is inserted between lever arm 30 and end wall 37 of the chimney, the thickness of the coin will cause indicator 43 to assume any one of the several positions marked by the letters on the scale and show the denomination of the inserted coin.

Obviously the coin indicator shown in Fig. 7 may be employed for purposes other than that of just indicating the denomination of coins. It may readily serve to control the acceptance or rejection of coins in coin operated devices. However, as applied to the toy bank illustrated in Fig. 1, it serves to add interest to the user of the device.

20 While in the foregoing more or less specific constructions of the toy bank and its mechanism are described, it is quite obvious that changes and improvements may be incorporated therein without departing from the broad scope of the 25 present invention as covered by the annexed claims.

I claim:

1. In a coin-controlled door latching structure for a toy bank, the latter including a substantially closed compartment having an opening, a transparent member permanently secured over said opening and a movable door adapted to normally cover said opening and to assume an adjacent position relative to said transparent member; an arcuate detent extending from the door into the compartment and comprising a larger and a smaller portion, the latter being operative in a slot provided in the transparent member, an abutment formed at the junction of the larger and smaller detent portions, a coin chute extending above and being directed into said compartment, thereby freeing the door for manual opening provided in said chute, a lever structure composed of spaced inner and outer arms and having a common pivot, its inner arm being operative within one of the chute slots, its outer arm terminating in a hook and coacting with said detent; said door being adapted to assume either its aforesaid normal closed or an open position, to which latter position the door is operated manually; a spring element for said lever structure adapted to cause the latter to swing in one direction, thereby urging the inner arm toward one wall of the chute and the outer arm into engagement with the detent abutment whereby the door is kept closed, said inner arm being adapted, when a coin is inserted in the chute, to move away from the chute wall, to momentarily retain the coin in the chute, and to cause the disengagement of the hook from the abutment, two transversely disposed, vertical slots being; a hook elevating member provided at the free end of the larger detent portion and being adapted, when the door is moved to its fully open position, to engage and raise the hook and thus to swing the lever structure against the tension of the spring element, whereby the inserted coin becomes released and drops into the compartment, and means associated with the chute and cooperating with the inner arm for indicating the denomination of an inserted coin.

2. In a coin-controlled door-latching structure for toy banks or the like, having a bank chamber and a swingable door, a coin chute extending partly above and partly into the bank

chamber, said coin chute having a relatively wide coin-receiving slot and a shorter slot disposed centrally to and crossing the wide slot, a double arm lever structure associated with the chute, one of its arms being curved and being operative within the shorter slot and normally engaging with its curved portion one of the end walls of the shorter slot, said curved arm being adapted to be moved from its normal position by a coin inserted into the wide slot and to temporarily retain the coin in that slot, the other lever arm having a hook end and extending into the bank chamber, an arcuate detent element provided at the upper, interior edge of the door and having an abutment normally engageable by the hook end of the other lever arm when said curved lever arm is in its normal position, whereby the door is kept in closed position, said abutment also serving for limiting the opening movement of the door, when released by said hook end at the time the curved lever arm retains a coin in the chute, hook end actuating means provided with said detent element for imparting a coin-releasing movement to said curved arm of the lever structure when the door approaches its full opening position, spring means for normally urging the lever structure to a position at which its curved arm abuts with that one wall of the shorter slot, while the hooked end of its other arm is kept in engagement with said abutment.

3. In a coin-controlled mechanism for coin-operated devices, including a coin receptacle, a coin receiving chute extending partly into and partly outside of said receptacle, said chute having a relatively long coin-receiving slot and a shorter slot, the latter crossing the long slot at right angles substantially at its center, a bell crank lever structure pivotally mounted beneath said chute, one of its arms being curved and extending into the shorter slot, the other bell crank arm extending with its free end into said receptacle, spring means associated with said other arm for urging its free end downwardly and thus causing the curved arm to normally engage one of the ends walls of said shorter slot, said curved arm being adapted to be moved against the tension exerted by said spring means as a coin is inserted into the long slot and to engage one face of the coin and to first momentarily retain the coin within the long slot, and, thereafter, to release the coin when the free end of said other crank arm is moved upwardly, thereby causing the curved arm to move toward the opposite end wall of the shorter slot so that it clears said long slot and permits the coin to drop; a revolving detent operable in the path of operation of the free end of said other crank arm and being adapted to either elevate that other arm or release it to its lowermost position, depending upon the relative position of the detent in respect to the free end of said other arm.

4. In a mechanism for coin-operated devices, a substantially tubular coin chute having a coin receiving slot and another intersecting slot transverse thereto, a bell crank having spaced but jointly pivoted arms one arm being operative in said transverse slot, the other, outer arm terminating in a hook, a revolving detent composed of two joined smaller and larger segments and movable to either of two end positions in a plane transverse to the direction of operation of said outer arm and having an abutment at the juncture of its segments adapted to become engaged by said hook for holding the detent in one end

position, a fixed stop engageable by said abutment for stopping the detent at the other end position, a hook raising element on said detent for elevating the hook when the detent is in that other end position, and a spring member engaging the bell crank for normally urging its one arm toward an end wall of said transverse slot, thereby exerting pressure against one face of a coin inserted into said coin-receiving slot and temporarily holding it against one wall of the coin receiving slot, said spring member also normally urging said outer arm into engagement with said detent; said hook of the bell crank being raised from said abutment by insertion of said coin and coaction of said one arm therewith, and allowing said detent to be moved to said other end position, whereat said hook is further elevated by the said hook raising element, effecting a further movement of said one arm in a direction opposite to that induced by said spring member, to an extent whereby the temporarily held coin is released.

5. In a toy bank or the like, a substantially fully closed bank body having a lockable closure arranged in its base, a single door opening provided in one wall of the body, an opaque door swingable outwardly in respect to said door opening, means for normally urging the door to its closed position, a transparent cover extending over and fully sealing the door opening from within, an arcuate element associated with and forming a part of the upper edge of the door, a slot in said transparent cover for permitting the movement therethrough of said arcuate element, said element comprising smaller and larger segments of different radii characterized by a step-formation at the juncture of the segments; said step-formation being adapted to engage one edge of the slot when the door is swung open, thus serving as limiting stop for the outward movement of the door; a wedge-shaped member formed on the top face and at that end of the larger segment which is remote from said step-formation; a coin chute extending from and beyond the bank body, a spring-loaded bell crank structure operatively associated with the chute, one of its arms normally bearing against one wall of the chute, its other arm being adapted to engage the step-formation, thus locking the door in closed position, insertion of a coin into said chute between said one wall and said one arm, releasing said other arm from engagement with said step formation, the wedge-shaped member of said arcuate element being adapted to further elevate said other arm of the bell crank when said door is opened, thereby causing that one arm thereof to assume a position away from that one chute wall.

6. In a toy bank as per claim 5, said coin chute having two vertical slots disposed at right angles to one another, one slot being longer and serving for the reception of coins, the shorter slot being adapted to accommodate said one arm of the bell crank structure, said other arm terminating in a hook normally adapted to engage said step-formation of the said element for keeping the door in closed position, insertion of a coin into said chute between said one wall and said one arm releasing said other arm from engagement with said step formation, said hook being further adapted to disengage said step-formation, and thus permit the manual opening of the door, when the said one arm is actuated by and momentarily holds in place a coin inserted into the longer slot of the chute; said wedge-shaped

member of the arcuate element being adapted to further elevate said other arm of the bell crank when said door is opened, thereby causing that one arm thereof to assume a position away from that one chute wall to a coin-releasing position to the end that the released coin may be observed falling into the toy bank interior through the transparent cover sealing the door opening.
